DESIGN FOR A FIRE-PLACE HEATER.

Design No. 13,608, dated February 13, 1883.

UNITED STATES PATENT OFFICE.

H. CLAY BASCOM, OF TROY, AND TOBIAS S. HEISTER, OF LANSINGBURG,
ASSIGNORS TO THE SIMONDS MANUFACTURING COMPANY, OF NEW
YORK, N. Y.

DESIGN FOR A FIRE-PLACE HEATER.

SPECIFICATION forming part of Design No. 13,608, dated February 13, 1883.

Application filed December 30, 1882. Term of patent 7 years.

To all whom it may concern:

Be it known that we, H. CLAY BASCOM, a citizen of the United States, residing in the city of Troy, in the county of Rensselaer and 5 State of New York, and TOBIAS S. HEISTER, a citizen of the United States, residing in the village of Lansingburg, in said county and State, have jointly invented and produced a new and original Design for Fire-Place Heaters, of which the following is a specification, reference being had to the accompanying cut, print, or engraving, representing said new design.

The design for the canopy A consists of the 15 outer arch molding, *a*, inner arch molding, *b*, intermediate arch-band *c*, and upper corner parts, *d*, all shaped, ornamented, and arranged together so as to present substantially the same appearance as is represented in the aforesaid engraving.

The design for the heater proper consists of the top section, B, combustion-chamber section 25 C, fire-box section D, and ash-pit section E, all shaped, proportioned, arranged together, and ornamented so as to present substantially the same appearance as is represented in the accompanying print.

The design for the top section, B, consists of the hemispheric cap part F and the top plate, 30 G, all shaped, proportioned, ornamented, and arranged together substantially as shown in the aforesaid cut.

The design for the hemispheric cap part F consists of the two lower longitudinal bands, *e*, 35 *f*, having therein the two series of inverted arches, as shown, the circular top part, *g*, and the two upper longitudinal bands, *h* *i*, having the series of sprig-like and scroll-form ornaments, all shaped and arranged substantially 40 as shown in the aforesaid print.

The design for the top plate, G, consists of the straight front edge part, *j*, and end edge parts, *j'*, meeting in front at obtuse angles, and the upper concavely-inclined surface, *k*, having 45 the front ornament, *l*, and end ornaments, *m*, all shaped and arranged together substantially as shown in the aforesaid engraving.

The design for the combustion-chamber section C consists of the upright angular front

corner columns, *n*, the two front four-light doors, 50 *o*, and the four-light end panel, *p*, all shaped, ornamented, and arranged together substantially as shown in the aforesaid cut.

The design for the fire-box section D consists of the top plate, H, having straight front and 55 end edges, the corner pedestals, *q*, the two two-light front doors, *r*, and the end panel, *r'*, all shaped, ornamented, and arranged together substantially as represented in the aforesaid print. 60

The design for the foot-rail I consists of the compound ornaments *s* on the convex surface of its semicircular end parts and the middle compound ornament, *s'*, all shaped and arranged together substantially as shown in the 65 aforesaid cut.

The design for the ash-pit section E consists of the top plate, J, front plate, K, end plates, L, and base-plate M, all shaped, proportioned, 70 ornamented, and arranged together so as to present substantially the same appearance as is represented in the aforesaid engraving.

The design for the plate J consists of the downwardly and outwardly inclined front and end edge parts, *t* *t'*, and intervening rounded 75 corner parts, *t''*, with the series of upwardly-pointing ornaments *t''* thereon, the top surface, *u*, and the middle front ornament, *v*, corner ornaments, *w*, intervening ornaments, *x* *y*, and end ornaments, *z*, all shaped and arranged together substantially as shown in the aforesaid print. 80

What we claim as our joint invention is—

1. The design for the canopy A, consisting of the parts *a b c d*, all shaped, arranged together, and ornamented as described. 85

2. The design for the heater proper, composed of the sections B C D E, all shaped, proportioned, arranged together, and ornamented as described. 90

3. The design for the top section, B, composed of the parts F and G, shaped, proportioned, arranged together, and ornamented as set forth. 95

4. The design for the hemispheric cap part F, consisting of the parts *e f g h i*, shaped, ornamented, and arranged together as described.

5. The design for the plate G, consisting of

the parts *j j' k l m*, all shaped and arranged as set forth.

6. The design for the section C, composed of the parts *n o p*, all shaped, arranged together, and ornamened as set forth.

7. The design for the section D, composed of the parts *H q r r'*, all shaped, arranged, and ornamened as described.

8. The design for the foot-rail I, consisting of the form shown, in combination with the ornaments *s s'*, shaped and arranged as set forth.

9. The design for the section E, composed of

the parts *J K L M*, shaped, proportioned, arranged together, and ornamented as set forth. 15

10. The design for the plate J, consisting of the ornamental parts *t t' t' t' u v w x y z*, all shaped and arranged as described.

In testimony whereof we hereunto set our hands, in the presence of two subscribing witness, this 12th day of December, 1882.

H. CLAY BASCOM.
TOBIAS S. HEISTER.
